ATTORNEYS

UNITED STATES PATENT OFFICE.

WILLIAM G. BELL, OF PHILADELPHIA, PENNSYLVANIA.

TIP FOR CRUTCHES.

Application filed September 3, 1921. Serial No. 498,456.

To all whom it may concern:

Be it known that I, WILLIAM G. BELL, a citizen of the United States, and a resident of Philadelphia, in the county of Philadelphia and State of Pennsylvania, have invented certain new and useful Improvements in Tips for Crutches, of which the following is a specification.

This invention relates to improvements in tips for crutches.

The object of the invention is to provide a crutch tip adapted to serve as a pneumatic cushion for the crutch during the use thereof and to absorb the shocks which may be imposed upon the end of the crutch.

A further object of the invention is that the tip be adapted to grip the surface upon which the same may contact during the use thereof.

20 A further object of the invention is that the pneumatic cushion of the tip be adapted to be inflated to any degree desired. It is also an important object of the invention that the inflated cushion be adapted to hold 25 the parts of tip in proper position.

Other objects and objects relating to details of construction will hereinafter appear in the detailed description to follow.

20 The invention is illustrated by way of example in the accompanying drawings, in which:—

Figure 1 is a perspective view of the lower end of a crutch, showing my improved tip applied,

35 Figure 2 is a vertical sectional view of the same,

Figure 3 is a section taken on the line 3—3 of Figure 1 when looking in the direction of the arrows.

40 Figure 4 is a view similar to Figure 2 but showing a modified form of tip.

Referring to the drawings in detail and particularly to Figures 1 to 3 inclusive, 10 indicates generally the stock of a crutch which tapers toward its lower end in the usual manner and terminates in a reduced threaded portion 11.

50 In carrying out the present invention, there is provided a nipple 13 which tapers slightly toward its lower end as shown and has its upper end interiorly threaded as at 14 adapted to receive the threaded end 11 of the crutch. The lower end of the nipple 13 terminates in a pair of legs 15 which in turn terminate in a head 16, said head being

formed with a clincher bead 17. The openings existing between the adjacent sides of the legs 15 are preferably oblong in shape as shown at 18 Figure 1.

A shoe 19 is provided, preferably of rubber which has its bottom surface concave as at 20. The shoe is hollow and tapers toward its upper end and terminates in an annular bead 21 which is adapted to be received by the clincher bead 17. The inner wall 22 of the shoe is semi-spherical in shape and the lower end of the head 16 complementary thereto as at 23. Within the shoe 19 there is positioned a pneumatic cushion 24 which is preferably of rubber and has communicating therewith an inflation stem valve 25 which is of the usual construction, said valve extending through the head 16 and having threaded on the upper end thereof a cap 26. The cap 26 is formed with a flange 27 the peripheral edge of which is serrated in order that the same may be manipulated by the fingers of an operator.

In the use of the present invention the same is associated with a crutch stock as shown in the drawings. The cap 26 may now be removed and the rubber cushion 24 inflated to any degree desired. The inflation of this cushion will distend the walls of the shoe 19 and also securely bind and hold the shoe against removal from the clincher bead 17. The cushion 24 will serve to absorb in an efficient manner the shock imposed upon the end shoe 19. Also as is obvious the concave bottom 20 of the shoe will insure against the same slipping upon the surface with which it contacts during the use thereof. It is believed the other advantages flowing from my invention, viz., the ease and convenience with which the cushion may be inflated, etc., may be apparent.

Referring to Figure 4, the crutch stock 28 in this instance carries at its lower end the usual tip socket 29 which is interiorly threaded and terminates at its lower end in the outwardly flared portion 30. For instances of this kind I provide a modified form of tip, comprising a nipple 31 which is threaded at its upper end for reception by the socket 29. The upper end of the nipple is closed as at 32 and its lower end flared outwardly as at 33 and then terminating in a clincher bead 34 adapted for receiving the annular bead 35 formed upon the upper end of the shoe 36. The lower

- end of the nipple is also formed with a closure as at 37 which is curved so that the same may be complementary to the inner wall of the shoe 36. An inflation valve stem 38 extends through the closure 37 and communicates with the interior of the pneumatic cushion 39; and said valve stem also extends through the upper end closure 32 of the nipple and carries a cap 39'.
10 In the present form of the invention the tip must be removed for inflating the pneumatic cushion, otherwise the operation is substantially the same as recited for the tip shown in Figures 1 to 3.

15 I claim:

1. A crutch tip comprising a head with a clincher bead formed upon the lower face thereof and its upper end formed with a pair of legs or struts which terminate in a sleeve adapted to receive the lower end of a crutch stock, a resilient hollow shoe having its upper end formed with a bead adapted to be received by said clincher bead, a pneumatic pad within said shoe, and an inflation valve stem extending through said head and communicating with said pneumatic pad and having its upper end disposed between said legs whereby the pneumatic pad may be inflated.
- 20 2. A crutch tip comprising a head with a clincher bead formed upon the lower face thereof and its upper end formed with a pair of legs or struts which terminate in a sleeve adapted to receive the lower end of a crutch stock, a resilient hollow shoe having its upper end formed with a bead adapted to be received by said clincher bead, a pneumatic pad within said shoe an inflation valve stem extending through said head
- 25 and communicating with said pneumatic pad and having its upper end disposed between said legs, and a cap for the upper

end of the valve stem adapted to be easily removed or positioned.

3. A crutch tip terminating in a head 45 with a clincher bead formed therewith, a resilient shoe having its upper face concaved complementary to the lower face of the tip, a bead formed about the upper edge of the shoe and adapted to be fitted into the 50 clincher bead of the crutch tip, a spherical pneumatic pad interposed between the shoe and lower end of the crutch tip head, and means whereby the pad may be inflated.

4. A crutch tip comprising a head, means 55 formed upon the lower face of said head whereby a hollow resilient shoe may be connected therewith, a pneumatic pad within the shoe, an inflation stem extending through the head and terminating at its one 60 end in the pneumatic pad, and means whereby the head may be secured to a crutch stock to serve as a tip therefor, and said means being adapted to permit access to the outer end of the inflation stem whereby 65 to inflate said pneumatic pad.

5. A crutch tip comprising a head having a clincher bead formed upon its lower face, a hollow resilient shoe cup-shaped in formation and having a bead formed about its 70 upper edge and exteriorly thereof, said bead being adapted to be received by said clincher bead, a pneumatic pad interposed between the bottom of the shoe and the bottom face of the crutch tip head, an inflation stem 75 extending through the head and having its one end communicating with the interior of the pneumatic pad whereby the pneumatic pad may be inflated and thereby to hold the shoe against dislodgement from 80 the clincher bead and also to increase the resiliency of said shoe.

WILLIAM G. BELL.
